UNITED STATES PATENT OFFICE.

DAWSON M. TAGGART, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,276,442.

Specification of Letters Patent. Patented Aug. 20, 1918.

Application filed November 17, 1917. Serial No. 202,516.

To all whom it may concern:

Be it known that I, DAWSON M. TAGGART, a citizen of the United States, residing at East Orange, in the county of Essex and 5 State of New Jersey, have invented certain new and useful Improvements in Telephone-Exchange Systems, of which the following is a full, clear, concise, and exact description.

This invention relates to telephone exchange systems, and more particularly to such systems of the central energy type employing connecting or link circuits provided with apparatus for automatically applying ringing current to the called-for line upon 10 connection being made therewith. The object of this invention is to provide a system of this character in which the connecting or link circuit is provided with apparatus for preventing the application of ringing current to a busy line should the link circuit be connected therewith.

In accordance with the various features of this invention, a connecting or link circuit is provided with two local circuit relays 15 which function and coöperate upon the connection thereof with a telephone line to connect a source of ringing current therewith, and which coöperate in a different manner upon connection being made with a busy telephone line to prevent the connection of 20 the source of ringing current therewith. The link circuit is also provided with apparatus by means of which, after the called-for station has responded and ringing current 25 has been disconnected from the line, it is impossible to again apply ringing current thereto upon the accidental disconnection of the link or connecting circuit from the line and the reconnection therewith.

For a more complete understanding of this invention, reference should be had to the following description considered in connection with the accompanying drawing illustrating one embodiment thereof.

In the drawing there is shown a telephone line A extending to a central office X and there suitably connected with a cord circuit C. A telephone line B terminates at a central office Y, and a trunk circuit D may be 5 employed to connect the cord circuit C with the telephone line B. The telephone lines A and B and the cord circuit C are of the usual type, while the trunk circuit D embodies the above mentioned features of this invention. 10 The apparatus shown within the dotted lines

in the upper left-hand corner of the drawing is located at the central office X, while the other apparatus shown in the drawing is located at the central office Y. This invention can probably be best understood from a 15 description of the operation of the system illustrated in the drawing, and it will be so described.

The operator at central office X, upon being advised by the initiating subscriber A 20 that connection is desired with the line of subscriber B, may communicate over an order wire circuit (not shown) to the operator at the central office Y, the number of the wanted line, whereupon the operator at 25 central office Y assigns a trunk circuit to be used. Assuming that the assigned trunk circuit is trunk circuit D, the operator at central office X inserts plug 5 into jack 6 of the trunk circuit, thereby lighting the calling 30 supervisory lamp 9. Trunk relay 7 also operates over a circuit from battery through the winding of supervisory relay 8, ring contacts of the plug 5 and the jack 6, both windings of trunk relay 7 and tip contacts of the 35 jack 6 and the plug 5 to ground. Upon the operation of trunk relay 7, lamp 10 is lighted over a circuit from battery through lamp 10, resistance coil 11, alternate contact of trunk relay 7, normal contact of tripping 40 relay 12, normal contact of relay 13, and contact 14 of relay 15 to ground. The operator at central office Y, observing the lighted condition of the lamp 10, notes that the originating operator has connected the cord 45 circuit C with the proper trunk circuit. The operator at central office Y may thereupon 50 test line B to determine the idle or busy condition thereof. Assuming this line to be 55 idle, plug 20 of the trunk circuit D is inserted in jack 21 of the line B, whereupon relay 22 and cutoff relay 23 are operated over a circuit from battery through contact 24 of relay 15, left-hand winding of relay 22, sleeve contacts of the plug 20 and the jack 60 21, and the winding of cutoff relay 23 to ground. Relay 22, in operating, causes the 65 operation of relay 15 over a circuit from battery through the upper winding of relay 15, and contacts 25 and 26 of relay 22 to ground. The operation of relay 15 opens the circuit 70 through the left-hand winding of relay 22. Relay 22 thereupon releases, and establishes a circuit for relay 15, which may be traced 75 from battery through contact 27 and lower 80

85 sleeve contact of the plug 20 and the jack 21, and the winding of cutoff relay 23 to ground. 90 Relay 22, in operating, causes the operation of relay 15 over a circuit from battery through the upper winding of relay 15, and contacts 25 and 26 of relay 22 to ground. The operation of relay 15 opens the circuit 95 through the left-hand winding of relay 22. Relay 22 thereupon releases, and establishes a circuit for relay 15, which may be traced from battery through contact 27 and lower 100 105 sleeve contact of the plug 20 and the jack 21, and the winding of cutoff relay 23 to ground. The operation of relay 15 opens the circuit through the left-hand winding of relay 22. Relay 22 thereupon releases, and establishes a circuit for relay 15, which may be traced from battery through contact 27 and lower 110

winding of relay 15, contact 28 of relay 22, sleeve contacts of the plug 20 and the jack 21, and the winding of cutoff relay 23 to 5 ground. The operation of relay 15 removes a short circuit from the winding of ringing relay 30 which is of comparatively high resistance and which is now included in circuit with the lamp 10. The comparatively high resistance of this relay 30 causes the lamp 10 to be extinguished, while relay 30 operates, connecting to the line B a source of signaling or ringing current 31 for operating call bell 32 at station B. This signaling or ringing circuit may be traced from the source of 10 current 31 through the winding of the tripping relay 12, contact 33 of relay 22, lower alternate contact of ringing relay 30, ring contacts of the plug 20 and the jack 21, the call bell 32 and the condenser at station B, 15 tip contacts of the jack 21 and the plug 20, contact 34 of relay 15, upper alternate contact of ringing relay 30, and contact 35 of relay 22 to ground.

Upon the response of subscriber B, tripping relay 12 is operated, thereby removing 20 a short circuit from the right-hand winding of relay 13, which is thereupon included in circuit with the ringing relay 30 and operates. In operating, relay 13 establishes a locking circuit for itself from battery 25 through the lamp 10, resistance coil 11, alternate contact of trunk relay 7, and right-hand winding and alternate contact of relay 13 to ground. The closure of the alternate 30 contact of relay 13 also establishes a short circuit for the ringing relay 30, which thereupon releases, disconnecting ringing current from the line. The resistance of the 35 right-hand winding of relay 13 is comparatively high, so that the lamp 10 will not be lighted when included in circuit therewith. Upon the release of the ringing relay 30, supervisory relay 36 is operated, thereby 40 short-circuiting the left-hand winding of 45 trunk relay 7. The resistance in circuit with the winding of the supervisory relay 8 is thereby reduced, permitting the operation thereof. Upon the operation of supervisory relay 8 a shunt circuit including a resistance 50 coil 37 is established about the calling supervisory lamp 9, whereby the lamp is extinguished.

If the plug 20 should accidentally be disconnected from the jack 21 and reconnected 55 therewith, relay 15 will first release upon the removal of the plug, and upon the reinsertion thereof relay 22 will operate, followed by the operation and locking up of relay 15 and the release of relay 22 as hereinbefore 60 described. Ringing current therefore will not be reconnected with the line B for the reason that relay 13 is locked up under control of the trunk relay 7.

At the conclusion of the conversation the 65 subscribers restore the receivers to the

switchhooks. The restoration of the receiver to the switchhook by subscriber B releases supervisory relay 36, thereby again including the left-hand winding of trunk relay 7 in circuit with the winding of supervisory relay 8. Relay 8 thereupon releases, 70 causing the lighting of calling supervisory lamp 9, which, together with the answering supervisory lamp (not shown) of cord circuit C, serves as a disconnect signal to the 75 operator at central office X. Plug 5 may thereupon be withdrawn from the jack 6. Trunk relay 7 then releases and the lamp 10 is lighted over a circuit from battery 80 through lamp 10, resistance coil 11, normal contact of trunk relay 7, and contact 38 of relay 15 to ground. The lighting of this lamp 10 serves as a disconnect signal to the operator at central office Y, who may thereupon withdraw the plug 20 from jack 21, 85 restoring all apparatus to normal condition.

Assuming that, after subscriber B has restored the receiver to the switchhook and before the connection is broken down, as before described, the operator at central office 90 X wishes to signal the subscriber B. The momentary removal of the plug 5 from a jack 6 followed by the reinsertion thereof causes ringing current to be connected with the line B. This is brought about in the following manner: When plug 5 is withdrawn from the jack 6, trunk relay 7 releases, thereupon opening the locking circuit of relay 13 which, in turn, releases. Upon the reinsertion of the plug 5 into the jack 6, trunk relay 100 7 is again operated, whereupon an operating circuit is established through the winding of the ringing relay 30 which attracts its armatures, connecting ringing current to line B. The call bell at station B is therefore operated and when subscriber B removes the receiver from the switchhook, ringing current is disconnected from the called line and the calling supervisory lamp 9 is lighted in the manner hereinbefore described. If the operator at central office X wishes to communicate with subscriber B, the actuation of a listening key 39 connects the operator's telephone set in circuit so that this operator and the subscriber may converse. 115

If another trunk circuit similar to D or a cord circuit similar to C is connected with another jack of line B when the plug 20 is inserted into the jack 21 thereof, relays 22 and 15 will operate as before described, but 120 relay 22 will not release upon the actuation of relay 15. When relay 22 operates under these conditions, it is then locked up over a circuit from battery furnished through the sleeve contacts of the previously connected cord or trunk circuit, the sleeve contacts of the jacks of line B, sleeve contact of the plug 20, right-hand winding of relay 22 and contact 26 thereof to ground. 125 Upon the operation of relay 15 the ring- 13

ing relay 30 operates in the manner hereinbefore described, but, since contacts 33 and 35 of the relay 22 are now open, ringing current is not, and cannot be, connected to the line B. Immediately upon the operation of the ringing relay 30, relay 13 is connected across the tip and ring conductors of the trunk circuit D and is operated over a circuit from battery supplied through the other connected cord or trunk circuit, the ring contact of the plug thereof, ring contacts of the jacks of line B, ring contact of the plug 20, lower alternate contact of ringing relay 30, left-hand winding of relay 13, contact 40 of relay 22, upper alternate contact of relay 30, contact 34 of relay 15, tip contacts of the plug 20 and the jack 21, back to the other side of the battery in the other connected cord or trunk circuit through the tip contacts of the plug thereof and the jack engaged thereby. Relay 13, in operating, establishes a locking circuit through its right-hand winding and also short-circuits the ringing relay 30, which disconnects the relay 13 from the tip and ring conductors and closes through these conductors. Supervisory relay 36 then operates, short-circuiting the left-hand winding of the trunk relay 7, thereby permitting the operation of supervisory relay 8 to extinguish the calling supervisory lamp 9. Ringing current cannot be connected to line B when the cord or trunk circuit previously connected therewith is disconnected, for the reason that relay 13 is now locked up under control of the trunk relay 7.

This invention provides a simple system of the automatic ringing type in which it is a simple and easy matter to establish three-cornered connections.

What is claimed is:

1. A telephone exchange system comprising a telephone line, a link circuit for connecting therewith, a source of ringing current, a first relay in the link circuit responsive to the connection thereof with the line, a second relay energized upon the response of the first relay, and a ringing relay responsive to the energization of the second relay to connect the source of ringing current to the line when the first relay is de-energized.

2. A telephone exchange system comprising a telephone line, a link circuit for connecting therewith, a first relay in the link circuit energized upon the connection therewith of the line, a second relay responsive to the energization of the first relay, a ringing relay energized upon the response of the second relay, and a source of ringing current connected with the telephone line through contacts of the first relay when de-energized and contacts of the ringing relay when energized.

3. A telephone exchange system comprising

ing a telephone line, a link circuit for connecting therewith, a first relay in the link circuit energized upon connection thereof with the line, a second relay responsive to the energization of the first relay to cause the de-energization of the first relay, a locking circuit for the second relay completed upon the response thereof for rendering it independent of the first relay, a ringing relay energized upon the response of the second relay, and a source of ringing current connected with the telephone line through normally close contacts of the first relay and normally open contacts of the ringing relay.

4. A telephone exchange system comprising a telephone line, a link circuit for connecting therewith, a first relay in the link circuit energized upon connection with the telephone line, a second relay responsive to the energization of the first relay for causing the de-energization thereof, a ringing relay, an operating circuit therefor completed upon the response of the second relay, and a source of ringing current connected to the line through contacts of the first relay when de-energized and contacts of the ringing relay when operated.

5. A telephone exchange system comprising a telephone line, a link circuit connected therewith, a second link circuit, a first relay therein responsive to the connection thereof with the telephone line, a locking circuit for the first relay established upon the response thereof and including engaged contacts of both link circuits in the telephone line, a second relay energized upon the response of the first relay to open the initial energizing circuit thereof, a ringing relay operating upon the energization of the second relay, a source of ringing current, and a fourth relay co-operating with the ringing relay to control the connection of the source of ringing current to the telephone line and responsive to the operation of the ringing relay to cause the de-energization thereof.

6. A telephone exchange system comprising a telephone line, link circuits for connecting with the line, a first relay in one of the link circuits energized upon connection therewith of the telephone line, a second relay responsive to the energization of the first relay, a ringing relay energized upon the response of the second relay, a source of ringing current, circuit leads connected with the telephone line by the energization of the ringing relay and with the source of ringing current by the de-energization of the first relay when the line connected with is idle, and a locking circuit for the first relay established upon the energization thereof when connection is made with the line to which another link circuit is already connected, thereby preventing the connection

of the circuit leads with the source of ringing current.

7. A telephone exchange system comprising a telephone line, link circuits for connecting therewith, a first relay in each link circuit operating upon connection thereof with the telephone line, a second relay responsive to the energization of the first relay for causing the deenergization of the first relay when no other link circuit is connected with the telephone line, a locking circuit for the first relay established upon the energization thereof when another link circuit is already con-

nected with the same line, a ringing relay energized upon the response of the second relay, a source of ringing current, and circuit leads over which current from said source is transmitted to the telephone line and including normally closed contacts of the first relay and normally open contacts of the ringing relay.

In witness whereof, I hereunto subscribe my name this 14th day of November A. D., 1917.

DAWSON M. TAGGART.
